HORACE H. BURDETT, OF HOPEDALE, MASSACHUSETTS, ASSIGNOR TO DRAPER CORPORATION, OF HOPEDALE, MASSACHUSETTS, A CORPORATION OF MAINE.

BOBBIN-CLUTCHING MEANS FOR ROTATABLE SPINDLES.

Application filed November 5, 1926. Serial No. 146,329.

This invention relates to that type of spindle employed in spinning frames and similar machines in which bobbin clutching members are provided to fit within the base 5 of the bobbin and to expand therein, thus to maintain the bobbin in position during the spinning or other operation.

It is the object of the present invention to provide a simple and efficient form of construction in which the pressure of the bobbin clutching members shall be exerted symmetrically and evenly radially of the spindle and in which the force of centrifugal action shall be utilized to the fullest extent 15 in increasing the pressure when the spindle is rotated.

It is the further object of the invention to provide a construction in which the parts are so constructed as not to be likely to get 20 out of order or fail to function.

It is the further object of the invention to provide a construction in which the parts shall be protected against clogging from fly or lint.

25 It is the object of the invention to provide a construction in which the movement of the parts shall be of a character as to be subject to the minimum amount of wear and one in which any part may be readily replaced if desired or found necessary.

30 These and other objects and features of the invention will appear more fully from the accompanying description and drawings and will be particularly pointed out in the claims.

35 As the general construction and operation of spinning and similar spindles with bobbin clutching members are well known and familiar to those skilled in the art, it will only be necessary here to illustrate and describe 40 the parts directly concerned with the present invention.

In the drawings:

Fig. 1 is a view chiefly in central vertical 45 cross section of a portion of a spindle embodying a preferred form of the invention, the section being taken on the line 1—1 of Fig. 4.

Fig. 2 is a view similar to Fig. 1, the section being taken on the line 2—2 of Fig. 4.

50 Fig. 3 is a side elevation of a portion of the construction shown in Figs. 1 and 2.

Fig. 4 is a top plan view partially broken away and partially in horizontal cross sec-

tion on the line 4—4 of Fig. 1, showing the 55 same construction.

In the preferred construction illustrated, the blade 1 of the spindle is generally of the usual form and has rigidly secured thereto, preferably by a driving fit, the whirl 2. In 60 the preferred construction, the whirl is extended upwardly to form an integral sleeve 3 concentric with and closely fitting the blade. This sleeve consequently rotates with the blade. Between the ends of the sleeve 65 the blade 1 is preferably formed with a section 4 of reduced diameter. The upper surface 5 of the whirl is flat and a metal cap having a flat top 6, the upper surface of which forms a bobbin rest, and a depending 70 annular flange 7 is secured to the whirl against the surface 5, preferably by being driven on with a driving fit. A collar 8 is secured to or driven on the blade at the upper end of the sleeve and is provided with 75 a depending flange 9 interlocking with the sleeve. The outer or exterior surface of this collar merges into that of the sleeve.

75 The sleeve 3 is provided with a plurality of symmetrically arranged longitudinal 80 slots, herein shown for convenience four in number. These slots at their lower ends 10 extend radially through the top portion of the whirl beneath the cap forming the bobbin rest and the side walls 11 of these slots 85 throughout their length extend parallel to the central, vertical, radial planes of the slots.

85 A bobbin clutching member and a spring 90 therefor are positioned by and movable in each one of the slots in the sleeve. Thus the bobbin clutching members and springs are positioned symmetrically around the blade and extend longitudinally thereof. The 95 clutch members are both angularly and bodily movable radially of the blade, that is, they both rock and move bodily in the slots in the sleeve. The outward movement of the clutch members is limited at both ends, in the construction illustrated, at the 100 upper end by the flange 9 of the collar 8 and at the lower end by the inner perimeter of the cap forming the bobbin rest. The 105 springs, which are located between the blade and the clutch members, are so arranged as to constitute radially yielding means acting against the clutch members intermediate their ends. In other words, the outer pres-

sure of the springs is exerted at a point intermediate the ends of the clutch members.

In the preferred construction illustrated, the springs 12 are shown as of a flat leaf form and stand vertically with their flat surfaces tangential to the blade, each spring being positioned by the side walls 11 of the slot within which it is located. The upper and lower ends of these springs are held 10 against inward radial movement while their intermediate portions are yieldable radially toward and from the blade. This is preferably secured by allowing the springs to contact at their upper and lower ends with the 15 main body of the blade while their intermediate portions span the reduced section 4 of the blade.

The bobbin clutching members 13 are shown as made of solid metal of substantial 20 radial thickness. Each fits closely between the side walls 11 of the slot within which it is mounted and is provided at its lower end with a foot or exterior flange 14 seated in the section 10 of the slot and extending 25 beneath the bobbin rest cap and is provided at its upper end with an inner upwardly extending flange 15 inside of the flange 9 of the collar 8. Each bobbin clutching member at its inner surface has a fulcrum engagement 30 intermediate and preferably about midway its ends with its corresponding spring 12. From this point or line of fulcrum engagement the opposed surfaces of the clutch member and cooperating spring diverge 35 above and below the fulcrum. This allows the bobbin clutching member to rock angularly in the slot. In the construction illustrated, this result is secured by having each spring straight and flat and forming the inner surface of the bobbin clutching member 40 at its lower portion 16 inclined downwardly and outwardly and at its upper portion 17 inclined upwardly and outwardly. Normally the construction is such that when the 45 springs are at rest or not exerting radial pressure, the bobbin clutching members are in their outermost positions and in contact with the springs, as shown in Fig. 1. The outer bobbin engaging surfaces of the bobbin clutching members in this position present 50 a total diameter somewhat larger than that of the bobbin bore.

When, now, the bobbin is placed in position, as it is first slid over the upper ends of 55 the clutch members, it presses radially inward these upper ends so that the bobbin clutching members rock angularly in their slots against a relatively light pressure exerted by the springs. As the bobbin is slid further down, this pressure increases until the 60 bobbin clutching members are forced bodily inward against the full force of the springs and the outer bobbin engaging surfaces engage the bobbin throughout their length. 65 This increase in the outward pressure exert-

ed by the springs and the bobbin clutching members from a relatively light pressure to a relatively heavy pressure as the bobbin is placed in position is very effective, enabling the operator to slip the bobbin on easily and insuring the bobbin being gripped with sufficient firmness, when seated on the bobbin rest, as to rotate with the spindle. This is due to the fact that each bobbin clutching member at first rocks as a lever and then 75 moves bodily inward.

It will be observed further that the bobbin clutching members are of very substantial size. This means that the bobbin clutching members are relatively heavy and thus 80 highly responsive to centrifugal action when the spindle is rotating at full speed. Thus the gripping engagement of the bobbin clutching members with the bobbin is very substantially increased by centrifugal action 85 when the spindle is in operation while, when the spindle is stopped, the bobbin is gripped only as a result of the resiliency of the springs.

Owing to the fact that the bobbin clutching members fit closely between the side walls of the slots in the sleeve 3 and are closely enclosed at their upper ends by the collar 8 and at their lower ends by the bobbin rest cap, it is well-nigh impossible for 90 the collection of lint or fly to have any effect upon the operation of the bobbin clutching members. This is further prevented by the rocking movement of the clutch members in the slots of the sleeve. Furthermore, the construction is such that it is practically impossible for it to get out of order. Each 95 spring and each bobbin clutching member are positioned and held in a simple and effective manner and no amount of wear or usage tends to interfere with these positions or to change the character or symmetry of the operation.

Having thus described the invention, what is claimed as new, and desired to be secured by Letters Patent, is:

1. A rotatable spindle comprising a blade, a plurality of springs positioned symmetrically around the blade and extending longitudinally thereof with their ends held 115 against inward radial movement and with their intermediate portions yieldable radially toward and from the blade, a corresponding plurality of clutch members located radially outward, and extending longitudinally, of the respective springs and presenting outer surfaces for engaging the bobbin and inner surfaces having fulcrumed engagement intermediate their ends with the 120 springs, the opposed surfaces of the clutch members and springs diverging above and below the fulcrums, and means for limiting the radial outward movement of both ends of the clutch members, whereby when a 125 bobbin is slid over the clutch members, first 130

the upper ends thereof will rock inward engaging the bobbin with relatively light pressure, and then the clutch members will move bodily radially inward engaging the bobbin 5 throughout their length with a relatively heavy pressure.

2. A rotatable spindle having the construction defined in claim 1, together with a sleeve concentric and rotatable with the blade and 10 presenting longitudinal slots fitting the bobbin clutching members and within which slots the bobbin clutching members move radially and from which slots the bobbin clutching members project outwardly.

15 3. A rotatable spindle having the construction defined in claim 1, together with a sleeve concentric and rotatable with the blade and presenting longitudinal slots positioning the springs and the respective bobbin 20 clutching members and the side walls of which fit the side walls of the bobbin clutching members and permit the required movements of the bobbin clutching members and from which slots the bobbin clutching members project outwardly.

25 4. A rotatable spindle comprising a blade, a plurality of flat leaf springs positioned symmetrically around the blade and extending longitudinally thereof with their flat 30 surfaces tangential thereto and with their ends held against inward radial movement and with their intermediate portions yieldable radially toward and from the blade, a corresponding plurality of clutch members 35 located radially outward, and extending longitudinally, of the respective springs and presenting outer bobbin engaging surfaces and inner surfaces having fulcrumed engagement intermediate their ends with the 40 springs, the surfaces of the clutch members opposed to the springs diverging outwardly above and below the fulcrums, and means for limiting the radial outward movement of both ends of the clutch members, whereby 45 when a bobbin is slid over the clutch members, first the upper ends thereof will rock inwardly engaging the bobbin with relatively light pressure, and then the clutch members will move bodily radially inward 50 engaging the bobbin throughout their length with a relatively heavy pressure.

5. A rotatable spindle having the construction defined in claim 4, together with a sleeve concentric and rotatable with the blade and 55 presenting longitudinal slots fitting the bobbin clutching members and within which slots the bobbin clutching members move radially and from which slots the bobbin clutching members project outwardly.

60 6. A rotatable spindle having the construction defined in claim 4, together with a sleeve concentric and rotatable with the blade and presenting longitudinal slots, the side walls of which abut the edges of the 65 springs and thus position the springs and fit

the side walls of the bobbin clutching members and permit the required movements of the bobbin clutching members and from which slots the bobbin clutching members project outwardly.

7. A rotatable spindle comprising a blade, a plurality of clutch members positioned symmetrically around the blade and extending longitudinally thereof and bodily and angularly movable radially thereof, independent radially yielding devices located one between the blade and each clutch member and acting against the respective clutch members intermediate their ends, and means to limit the outward movement of the ends 70 of the clutch members, whereby as a bobbin is forced into position over the clutch members, the upper ends of said clutch members will first rock inward against a relatively light pressure and then the clutch members 75 will move bodily inward against a relatively heavy pressure and finally, when the bobbin is seated, engage throughout their lengths the bobbin bore.

8. A rotatable spindle comprising a blade, a plurality of clutch members positioned symmetrically around the blade and extending longitudinally thereof and bodily and angularly movable radially thereof, radially yielding means located between the blade and 80 the clutch members and acting against the clutch members intermediate their ends, means to limit the outward movement of the ends of the clutch members, and a sleeve concentric and rotatable with the blade and 85 presenting longitudinal slots fitting the bobbin clutching members and within which slots the bobbin clutching members move radially and from which slots the bobbin clutching members project outwardly 90 where- 95 by as a bobbin is forced into position over the clutch members, the upper ends of said clutch members will first rock inward against a relatively light pressure and then the clutch members will move bodily inward 100 against a relatively heavy pressure and finally, when the bobbin is seated, engage throughout their lengths the bobbin bore.

105 9. A rotatable spindle comprising a blade, a plurality of clutch members positioned 110 symmetrically around the blade and extending longitudinally thereof and bodily and angularly movable radially thereof, radially yielding means located between the blade and the clutch members and acting against 115 the clutch members intermediate their ends, means to limit the outward movement of the ends of the clutch members, a sleeve concentric and rotatable with the blade and presenting longitudinal slots fitting the bobbin 120 clutching members and within which slots the bobbin clutching members move radially and from which they project outwardly, and a collar on the blade closing 125 the upper ends of the slots and having 130

its exterior surface merging with the exterior surface of the sleeve whereby as a bobbin is forced into position over the clutch members, the upper ends of said clutch members will first rock inward against a relatively light pressure and then the clutch members will move bodily inward against a relatively heavy pressure and finally, when the bobbin is seated, engage throughout their 10 lengths the bobbin bore.

10. A rotatable spindle comprising the construction defined in claim 4, in which the radial thickness of the bobbin clutching members is substantially as great as the limits of the stated movement will permit, whereby the bobbin clutching members are relatively heavy and act by centrifugal force when the spindle is rotating with a further increased pressure throughout their length 20 against the bobbin.

11. A rotatable spindle comprising a blade, a plurality of clutch members positioned symmetrically around the blade and extending longitudinally thereof and bodily 25 and angularly movable radially thereof, ra-

dially yielding means located between the blade and the clutch members and acting against the clutch members intermediate their ends, and means to limit the outward movement of the ends of the clutch members, whereby as a bobbin is forced into position over the clutch members, the upper ends of said clutch members will first rock inward against a relatively light pressure and then the clutch members will move bodily inward against a relatively heavy pressure and finally, when the bobbin is seated, engage throughout their lengths the bobbin bore, and the said bobbin clutching members having a radial thickness substantially as great as the limits of the stated movement will permit, whereby the bobbin clutching members are relatively heavy and act by centrifugal force when the spindle is rotating with a further increased pressure throughout 40 their length against the bobbin.

30 In testimony whereof, I have signed my name to this specification.

45 HORACE H. BURDETT.
